UNITED STATES PATENT OFFICE.

FRANK E. MILLER, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

DOOR-OPERATING MECHANISM.

Application filed November 29, 1922. Serial No. 603,979.

To all whom it may concern:

Be it known that I, FRANK E. MILLER, a citizen of the United States, residing in Pittsburgh, in the county of Allegheny and State of Pennsylvania, have invented certain new and useful Improvements in Door-Operating Mechanism, of which the following is a specification.

This invention relates to railway dump cars and more particularly to that type in which the floor is provided with horizontal discharge doors and has for an object the provision of a plurality of door supporting means for each door, which are simultaneously movable out of door supporting positions and which are permitted to move into door supporting positions independently of each other.

Another object of the invention is to provide means whereby a plurality of discharge door supporting members are simultaneously movable out of door supporting positions and whereby said members are movable into door supporting positions independently of each other.

A further object of the invention is to provide a discharge door of a railway car with a plurality of supporting members which are simultaneously moved out of door supporting positions by slidable means operatively connected with the door supporting members.

These and other objects will be apparent from the following description.

Referring to the drawings in which like reference characters refer to like parts, Fig. 1 is a plan view of a portion of a railway car embodying the invention; Fig. 2 is a side elevational view of the same; Fig. 3 is an enlarged sectional view taken on the line 3—3 of Fig. 2; and Fig. 4 is a side elevational view similar to Fig. 2 in which the operation of the invention is illustrated.

Referring now in detail to the drawings, the reference character 1 indicates the side wall of a railway car and 2 indicates the discharge doors which are preferably hinged to or adjacent the center sill 3 and having their free edges adjacent the side wall 1. Each of the doors 2 may be made of wood or metal and constructed in any preferred manner. Each of these doors is provided with strengthening members 4, each of

which is preferably U shaped in cross section for the greater part of its length and having a horizontal flange 5 which is secured to the door. These members extend outwardly beyond the free edge of the door and preferably beyond the side wall 2 and are adapted to be engaged by members 6 to support the door in closed position. The outer end portion of these members 4 instead of being U-shaped in cross section are provided with top portions 7 thus forming sockets for the reception of a bar or other suitable door closing means.

The members 6 are spaced apart and adjacent their upper ends are pivotally connected with bracket members 8 which are secured to the side wall 1. Each of the members 6 adjacent its lower end is provided with a ledge 9 the upper surface of which is adapted to engage with the lower surface of the outer end portion of one of the members 4 and when in such engagement will support the door in closed position. The pivot points of the members 6 are so located that these members will, after they have been moved out of engagement with the members 4, move by gravity to their proper door supporting positions. There are two members 6 for each discharge door, which members are spaced apart and when operated preferably move in opposite directions. Between these members a stationary member 10 is provided which is secured to the side wall 1 which member is provided with an outwardly extending T-shaped projection 11 on which a member 12 is slidably mounted. This member 12 is provided with a T-shaped opening 13, which is adapted to receive the projection 11 and when the members are in their operative positions it will be noted that they will be so interlocked that they will not become accidentally separated and yet free movement of the member 12 relative to the member 10 will be permitted. The member 12 is provided with a projection 14 on which the inner end portions of links 15 are loosely mounted, the outer end portion of each link being pivotally connected with one of the members 6. The member 12 is also provided with stop shoulders 16 which are adapted to engage with stop shoulders 17 formed on the member 10 to prevent the member 12 from moving downwardly an

excessive distance. When the stop shoulders 16 are in engagement with the stop shoulders 17 the lower end portion of the member 12 extends some distance below the member 10 and forms a striking block which may be struck by a sledge or other suitable tool to open the door.

In the present embodiment of the invention the upper ends of the links are provided with slots 18 through which the projection 14 on the member 10 extends. These slots are for the purpose of permitting one member 6 and link 15 connected therewith to move independently of the other member 6 and link and for the purpose of permitting both links to move relative to the member 12 all of which will hereinafter be fully described. It is to be understood, however, that these slots may be omitted in some cases where independent movement of the members 6 is not desired, in such cases the projection 14 will pass through circular openings in the links, such as illustrated at the opposite ends of the links, instead of through slots.

To hold the members 6 in locked door supporting positions, cams 19 are provided which are pivotally mounted on the member 10. Each of these cams is provided with a cam surface 20 which is adapted to be moved into and out of locking engagement with a vertical surface of one of the members 6 and is further provided with a lug 21 which when the cam is moved to locking position will engage a horizontal surface 22 formed on the member 6 and when in such engagement will prevent the cam from moving downwardly accidentally to an inoperative position.

Assuming the door to be in closed position as illustrated in Figs. 1, 2 and 3 and it is desired to open it, the operator moves the cam members 19 out of engagement with the members 6 and then strikes the lower end of the member 12 an upward blow with a sledge, causing the member 12 and adjacent ends of the links 15 to move upwardly, which in turn causes the members 6, through the medium of the links 15, to be pulled toward each other and out of engagement with the end portions of the members 4 secured to the door 2 at which time the door will be released and will move downwardly to its open position. After the door has been released and has moved downwardly the member 12 will move downwardly by gravity until the shoulders 17 engage the shoulders 18, and the members 6 and links 15 will move to their door supporting positions as shown in dot and dash lines in Fig. 4.

To close the door the operator inserts a bar or other suitable device in the end portion of one of the strengthening members 4 and by the use of such bar raises the door until the tops 7 of the members will engage

the lower bevelled surfaces 23 of the members 6 and a continued upward movement of the door will cause the members 6 to move toward each other and out of the path of the ends of the members as shown in full lines in Fig. 4 until such time as the door is closed at which time the members 6 will move by gravity to their door supporting positions, as illustrated in full lines in Fig. 1. It will here be noted that the members 6 are movable independently of each other when the door is being closed. This movement has been provided for the purpose of permitting either one of the members 6 to move into door supporting position independent of the other so that should the door or members 4 become so deformed that the end portions of these members 4 will not be in horizontal alignment when the door is being closed, one of the members 6 will be permitted to move into door supporting position. The door will thus be supported until the operator forces the other side of the door upwardly a sufficient distance to permit the other member 6 to move to its proper door supporting position. After the members 6 are in their proper door supporting positions the operator moves the cam members 19 into locking engagement with the members 6.

It will be apparent to those skilled in the art to which this invention appertains that changes in the form and arrangement of the several parts forming the invention may be made without departing from the spirit and scope of the appended claims.

Having thus described the invention, what I claim is new and desire to secure by Letters Patent is:—

1. In a dump car, a discharge door, a plurality of spaced members movable into and out of supporting positions with said door, and slideable means arranged between said members, for moving said members out of supporting positions with said door, simultaneously.

2. In a dump car, a discharge door, a plurality of spaced members pivotally mounted on said car adapted to support said door in its closed position, said members having door releasing movements in opposite direction, and means for simultaneously moving said members to their door releasing positions.

3. In a dump car, a discharge door, a plurality of pivoted door supporting members movable out of supporting position with said door, and link means for operating said members simultaneously, said link means being arranged below the pivot points of said members.

4. In a dump car, a discharge door, a plurality of members for supporting said door in its closed position, means for simultaneously moving said members out of door supporting position, and means whereby

said members are permitted to move into their door supporting positions independently of each other.

5. In a dump car, a discharge door, members pivotally connected with said car for supporting said door in its closed position, a stationary member secured to said car between said members, a member slidably mounted on said stationary member, and means connecting said slidable and pivotal members adapted to move said pivotal members out of door supporting position when said slidable member is moved.

6. In a dump car, a discharge door, members pivotally mounted on said car for supporting said door in its closed position and means for simultaneously moving said members out of their door supporting positions, said means comprising a vertically slidable member operatively connected with said door supporting members.

7. In a dump car, a discharge door, members pivotally mounted on said car for supporting said door in its closed position, and means for simultaneously moving said members out of door supporting positions, said means comprising a vertically movable member, and links connecting said member with said door supporting members.

8. In a dump car, a discharge door, members pivotally mounted on said car for supporting said door in its closed position, and means for simultaneously moving said members out of their door supporting positions, said means comprising a slidable member arranged between said door supporting members, and links connecting said slidable member with said door supporting members.

9. In a dump car, a discharge door, members mounted on said car adapted to be moved into and out of door supporting positions, means for simultaneously moving said members out of door supporting position and means whereby said members are permitted to move to door supporting positions independently of each other.

10. In a dump car, a discharge door, members mounted on said car and movable into and out of supporting positions with said door, a member slidably mounted on said car between said members and links operatively connecting said door supporting members and said slidable member.

11. In a dump car, a discharge door, a plurality of door supporting members pivotally mounted on said car and means for operatively connecting said members, said means causing said members to move toward each other simultaneously when the door is opened and permitting independent movement of said members when the door is being closed.

12. In a dump car, a discharge door, members pivotally mounted on said car adapted to be moved into and out of supporting posi-

tions with said door, a slidable member arranged between said members, connections between said slidable member and said members, whereby said members are simultaneously moved out of door supporting positions, and means whereby independent movement is permitted between said connections and said slidable member as said members move toward their door supporting positions.

13. In a dump car, a discharge door, hook shaped means for supporting said door, a member slidably mounted on said car, links operatively connecting said means and members, said links having slotted connections with said slidable member.

14. In a dump car, a discharge door, members mounted on said car for supporting said door in its closed position, and means for simultaneously moving said members out of supporting positions, said means comprising a vertically movable member, a projection on said movable member and links connected with said door supporting members and projection.

15. In a dump car, a discharge door, members pivotally mounted on said car adapted to move into and out of door supporting positions, a movable member mounted on said car, links pivotally connected with said pivotal members, and slidably connected with said movable member.

16. In a dump car, a discharge door, members pivotally mounted on said car adapted to be moved into and out of door supporting positions, and means for simultaneously moving said members in one direction and permitting independent movement of said members in the opposite direction.

17. In a dump car, a discharge door, members pivotally mounted on said car adapted to be moved into and out of door supporting positions, a member movably mounted on said car and connected with said members, for moving said members out of door supporting positions, and means whereby said pivotal members are moved to door supporting positions independently of each other and of said movable member.

18. In a dump car, a discharge door, members pivotally mounted on said car adapted to support said door in closed position, means for simultaneously moving said members out of door supporting positions, said means comprising links pivotally connected with said members, said links having slots formed therein, a member for operating said links and a projection on said member adapted to extend through said slots.

19. In a dump car, a discharge door, members pivotally connected with said car for supporting said door in its closed position, a member slidably mounted on said car, a link connecting each of said door supporting members and said slidable member, said link

being movable with said slidable member to move said door supporting member out of supporting position, and movable independently of said slidable member into door supporting position.

20. In a dump car, a discharge door, door supporting members pivotally connected with said car, means for simultaneously moving said members out of door supporting positions, said means comprising a movable member, links connecting said slidable member and said door supporting members, and loose connections for said links whereby said door supporting members may move to their door supporting positions independently of each other.

21. In a dump car, a discharge door, door supporting members pivotally connected with said car, said members having offsets adjacent their upper ends, members for locking said door supporting members in their door supporting positions and projections on said locking members adapted to engage said offsets when said locking members are in locking positions. 20

25 In testimony whereof I affix my signature in the presence of two witnesses.
